UNITED STATES PATENT OFFICE.

ARTHUR W. ROBINSON, OF MONTREAL, QUEBEC, CANADA.

DELIVERY PIPE FOR HYDRAULIC DREDGING MACHINES.

Application filed October 1, 1921. Serial No. 504,809.

To all whom it may concern:

Be it known that I, ARTHUR W. ROBINSON, a citizen of the Dominion of Canada, and a resident in the city of Montreal, county of 5 Hockelaga, Province of Quebec, and Dominion of Canada, have invented a new and useful Improvement in delivery pipes for hydraulic dredging machines of the class in which the spoils, consisting of earth, clay, 10 sand, gravel, etc., is transported from the dredging machine or other source of supply to the place of deposit by being pumped through a delivery pipe, together with a suitable admixture of water.

15 It is the purpose of this invention to obviate a serious difficulty experienced in the use of hydraulic dredging machines of the class stated which is that the spoils as they are pumped through the delivery pipe frequently tend to lodge and become fixed in the delivery pipe to such an extent as to seriously restrict the passage through the pipe and sometimes even to clog it entirely or to such an extent as to seriously interfere 20 with the operation of the machine and inevitably requiring a material increase in the power necessary.

It is the purpose of this invention, therefore, to obviate the stated difficulty by preventing the spoils during their passage through the pipe from accumulating or depositing themselves upon its bottom in such manner or to such a degree as will clog that same or interfere with the proper operation of the apparatus. In other words, under this invention the spoils in their passage through the delivery pipe are continually brought from the lower sections of the pipe to the upper sections thereof, and in 30 their attempt to fall under the action of gravity to the lower sections of the pipe they are inevitably maintained in a condition of practically homogeneous mixture with the propelling water so that all lodgment in the bottom of the pipe is prevented and the power required to effect the desired 35 delivery is materially reduced.

Referring to the drawing. Fig. 1 illustrates a longitudinal view of a section of 40 so called shore pipe partly in sections showing the invention.

Fig. 2 illustrates a transfer sectional view taken on the line 2.2. of Fig. 1.

In the drawings hereof I illustrate the 45 invention as applied to a section of what is known as "shore pipe", that is to say, a sec-

tional pipe which being used upon the land in contradistinction to that which is used upon floats, does not require the usual ball and socket or equivalent connection between 60 the lengths of pipe; on the contrary are merely telescoped together somewhat after the fashion of ordinary stovepipe.

It will, of course, be understood that the invention is as applicable to floating pipes 65 as to shore pipes, since the construction and method of operation, so far as this invention is concerned, are identical in both cases.

In the drawings 1 illustrates the pipe 2, 70 what I shall call in this specification "rifling ribs" because they have substantially the same effect upon the spoils during their passage through the pipe that the rifling of a cannon or rifle have upon the bullet or shell during its passage through the bore of 75 the arm, that is to say, they give the water and the spoils carried by it a pronounced whirling or spiral movement about the center of the pipe as an axis from the time they enter it until discharged at its end. These 80 rifling ribs are arranged spiralling running longitudinally of the pipe and radially from its interior surface inwardly. They may be made in any preferred form, and 85 of such width as desired. I prefer them to be made of relatively hard steel, and in the form of the angle iron shown, that is to say, having one radial member 3 and a base member 4, the base member being bolted or otherwise, suitably fastened to the interior 90 surface of the pipe. There may be as many of these rifling ribs employed in the pipe as desired. I ordinarily prefer three as illustrated. Their number, however, will depend to some extent upon the character of the 95 spoils being excavated and the power of the pump in propelling the water. In exceptional cases a single rib only may serve the purpose, in other cases two, three or more may secure the best results, and I prefer that 100 they should have a degree of spirality equal to from 15 to 25 times the diameter of the pipe, that is to say, in a section of shore pipe which, for example, may be twenty feet long, each of the rifle ribs may make one 105 complete convolution in the length of the pipe. On floating pipes which are frequently of much greater length than the shore pipe, each rib may make two or three complete convolutions in the length of each pipe 110 section. The ribs also may be discontinuous, that is to say isolated portions with a

space between them. Also they may be omitted altogether in the bottom of the pipe so as to permit stones to more readily pass.

In order that there may be no possibility 5 of the dredged material which sometimes, particularly in the case of harbor dredging, may include pieces of rope, wire, chain and other similar material from becoming lodged over the front end of the rifle ribs, I prefer 10 to bevel off both the base member 4 and the vertical or radial member 3 at their front end, that is to say, at the end first encountered by the spoils in their passage through the pipe, as shown at 5.

15 The operation is obvious as the pump forces the spoils which are puddled with a large percentage of water through the pipes, the radial rifle ribs will successively cause the current of water to follow a violent 20 spiral or whirling course through the pipes, which, of course, will catch and carry with it all of the spoils excepting perhaps the heavier parts, such as cobble stones and the like, and will carry them to the upper part 25 of the pipe and under the action of gravity they will attempt to fall through the spirally flowing current, but being caught thereby will be maintained in the upper and central portions of the pipe and be pre- 30 vented from depositing themselves in the lower portions as heretofore. Consequently, all lodgment of the spoils which heretofore have created the trouble will be avoided and

so far as the heavier elements, that is to say, cobble stones and the like, are concerned there never has been any difficulty in their delivery because the pumped current is so powerful that owing to their bulk they are rolled along and in due course delivered at the mouth of the pipe. The rifle ribs 40 will, of course, be made of sufficient strength and solidity to withstand the blows delivered upon them by the heavier material referred to.

It will be obvious to those who are familiar with such matters that the rifle ribs may be made in a variety of ways and of such radial width and degree of spirality, and as stated above, of such number as preferred, and that they may be built into or applied to the pipe also in such manner as may be preferred, and that various modifications may be made in the details of construction without departing from the essentials of my invention.

I claim—

In a delivery pipe for hydraulic dredges a radially and spirally arranged rifling rib made of rolled angle iron and extending from end to end of the pipe, one angle arranged radially of the pipe, the other acting as a base and immovably fastened to the interior of the pipe, the front end of the radial angle being beveled off.

ARTHUR W. ROBINSON.
